ALABAMA.

HEATER.

Application filed August 29, 1924. Serial No. 734,992.

This invention relates to water heaters and its primary object is to provide a steam heated water heater which will heat the water to a maximum degree with a minimum expenditure of heat energy.

Another object of the invention is to provide a heater any number of which may be connected in series to heat water by steam from a single source.

10 Still another object of the invention is to provide a heater which includes a pair of headers arranged and mounted in a water reservoir in a novel manner together with a series of connecting pipes or tubes.

15 With the preceding and other objects and advantages in mind, the invention consists in the novel combination of elements, construction and arrangement of parts and operations to be hereinafter specifically described, claimed and illustrated in the accompanying drawings, wherein:

Figure 1 is a vertical longitudinal sectional view of a heater constructed in accordance with our invention, and

25 Figure 2 is a horizontal sectional view taken on line 2-2 of Figure 1.

Referring to the drawings in detail where in corresponding characters of reference denote corresponding parts, throughout the 30 several views, the numeral 5 designates a water reservoir having a water inlet opening 6 adjacent its bottom and an outlet pipe 7 leading from its upper wall. This water reservoir 5 is formed from sheet metal and 35 surrounding the same is asbestos or other insulating covering 8.

Mounted in the receptacle or reservoir 5 and extending longitudinally thereof is a pair of headers 10 and 10' having their ends 40 reduced and received in openings 11 in the end walls of the reservoir. Leading from the lower header 10 is a steam outlet pipe 12 which may be connected to one or more reservoirs similar to the one shown for heat-

ing water therein as will be readily apparent.

Between the headers and substantially centrally of the reservoir is arranged a series of pipes or tubes by means of which a maximum amount of water in the reservoir will 50 be subjected to the steam passing therethrough and this series of pipes include a plurality of coils arranged in parallelism as suggested in Figure 2 and extending longitudinally in the reservoir. The said coils 55 are connected with the headers 10 and 10' by a plurality of pipes 14 which are of various lengths and disposed at an oblique angle with respect to the longitudinal axis of the 60 headers as best shown in Figure 2 of the drawings. Leading from the upper header 10' is a steam inlet pipe 15 which is in communication with a suitable source of steam as will be readily apparent.

While we have shown and described the 65 preferred embodiment of the invention, it is to be understood that changes in the arrangement of parts may be made and that we are only limited by the appended claim.

Having thus described the invention, we 70 claim:

In a water heater, an insulated reservoir, upper and lower steam headers longitudinally disposed in said reservoir, a steam inlet pipe for the upper header, a steam outlet pipe for the lower header, means of communication between said headers including coils arranged in spaced parallel relation with respect to each other and centrally disposed 75 longitudinally in said reservoir, a pipe connecting one end of each coil with one header and a pipe connecting the other end of each coil with the other header.

80 In testimony whereof we affix our signatures.

JOEL C. THOMAS.
JAMES F. HALLIDAY.
ADDIE HILL, JR.
